UNITED STATES PATENT OFFICE

122,626

DESIGN FOR A HAND-MIRROR FRAME OR THE LIKE

Cecil Harry Lawrence, Attleboro, Mass., assignor to Evans Case Company, North Attleboro, Mass.,
a corporation of Massachusetts

Application May 23, 1940, Serial No. 92,552

Term of patent 7 years

To all whom it may concern:

Be it known that I, Cecil Harry Lawrence, a citizen of the United States, residing at Attleboro, county of Bristol, and State of Massachusetts, have invented a new, original, and ornamental Design for a Hand-Mirror Frame or the like, of which the following is a specification, reference being had to the accompanying drawing, forming a part thereof.

In the accompanying drawing,

The dominant features of my design reside in the portion shown in full lines.

I claim as my invention:

The ornamental design for a hand-mirror frame or the like, as shown and described.

CECIL HARRY LAWRENCE.
